UNITED STATES PATENT OFFICE.

DONATO DI CARLO, OF PHILADELPHIA, PENNSYLVANIA.

TALKING-MACHINE.

1,353,324.

Specification of Letters Patent. Patented Sept. 21, 1920.

Application filed March 6, 1920. Serial No. 363,888.

To all whom it may concern:

Be it known that I, DONATO DI CARLO, a subject of the King of Italy, (having declared my intentions of becoming a citizen 5 of the United States,) residing at Philadelphia, in the county of Philadelphia and State of Pennsylvania, have invented certain new and useful Improvements in Talking-Machines, of which the following is a 10 specification.

One object of my present invention is to provide a talking machine of the cabinet type including a hole in its lid which will be normally closed by a door and to so construct the parts that the door can be automatically opened by the closing of the lid after the machine has been started and so that the reproduced sounds which are transmitted within the cabinet will pass out 20 through said hole in such manner as to be distinctly audible.

Another object is to make the parts of my improved machine of a simple and durable construction.

25 These objects, and other advantageous ends which will be described hereinafter, I attain in the following manner, reference being had to the accompanying drawings in which—

30 Figure 1 is a fragmentary side elevation of a talking machine made in accordance with my invention, shown partly in section, and illustrating the lid raised to permit the starting of the machine,

35 Fig. 2 is a view in sectional elevation showing the lid closed during the operation of the machine and also illustrating how a hole in said lid, normally closed by a door, can be opened to permit the reproduced 40 sound from within the cabinet to pass outwardly therethrough; the door being shown at an incline forwardly to serve as a means for deflecting the sound forwardly.

45 Fig. 3 is a view similar to Fig. 2 showing how the apparatus can be adjusted so that the door can be opened to a different degree of incline from that shown in Fig. 2.

50 Fig. 4 is a fragmentary sectional elevation showing the position of the parts when the machine is not intended for use and so that the door will effectively close the hole when the lid is shut,

55 Fig. 5 is a perspective view of certain of the parts of my invention,

55 Fig. 6 is an elevation, partly in section,

showing certain of the parts illustrated in Fig. 5, and

Fig. 7 is a modification showing the door made up of a number of parts or slats instead of being made in one piece as shown 60 in Figs. 1 to 4 inclusive.

Referring to Figs. 1 to 6 inclusive of the drawings, 8 represents the body portion of a talking machine cabinet having a platform 9 spaced downwardly from its upper 65 edge 10. A lid 11 is hinged at 12 at its rear edge to the rear of the body portion 8 above the platform 9. A tone arm 13 is positioned within the body portion and has an upwardly extending part 14 providing 70 an opening at its top for the outlet of the reproduced sounds. The tone arm 13 at its opposite end has a sound box 15 thereon for engagement with a record, such as indicated at 16 in Fig. 1. The lid 11 is preferably 75 made hollow so as to provide a space 17, and this lid at its top 18 has a hole 19 which, when the lid is closed, is directly above and in line with the outlet or top end of the tone arm 13; said outlet end of 80 the tone arm being preferably flared to provide an amplifier for the reproduced sounds.

A door 20 is hinged at its rear edge as shown at 21 to the rear edge surface of the lid which provides the hole 19; said door 85 being adapted to close the hole 19 as shown in Figs. 1 and 4. A plate 22 has screw holes 23 therein whereby it can be screwed to the platform 9, and this plate has an upright post 24 which adjacent its top has 90 a bracket 25 adjustably secured thereto by a set screw 26. The bracket 25 has a slot 27 through which a rod 28 is adapted to freely slide. The upper end of this rod is pivotally connected at 29 to the inner surface of the door 20. The lower end of the rod 28 is preferably provided with a terminal piece 30 which is of greater diameter 95 than the width of the slot 27 so that when the lid is raised the rod 28 will not pull out of the slot 27. It will be understood that any suitable means not illustrated can be provided for holding the lid 11 in its open position as shown in Fig. 1, such for example as the device used on various forms of 100 talking machine cabinets. The post 24 has a portion 31 of reduced diameter so as to provide a shoulder 32. A member 33 is swiveled on the portion 31 of the post 24 and rests on the shoulder 32. A sleeve 34 110

surrounds the portion 31 of the post 24 above the member 33 and serves as a spacer between the member 33 and the bracket 25 to prevent the member 33 from moving upwardly and the bracket 25 from moving downwardly. The member 33 has two extensions in the form of arms 35 and 36. The arm 36 is arranged at a lower level than the arm 35 due to the bending of the portion 37 of the arm 36 as clearly shown in Fig. 5.

With this construction it is obvious that the member 33 can be turned on the portion 31 of the post 24 as a pivot so that either 15 of the arms 35 or 36 can be positioned below the lower end of the rod 28 or if desired the member 33 can be swung so that no one of the arms 35 or 36 is under the lower end of the rod 28; such position being 20 shown in Fig. 4. The member 33 has a depending pin 38 and the post 24 has a pin or lug 39 serving as a stop. With this construction when the arm 36 is swung into a position below the lower end of the rod 28, 25 the pin 38 will strike the stop 39 and limit said swinging movement with the arm 36 in said position. With the above construction when it is desired to play the machine, the lid is raised into the position shown in 30 Fig. 1 and either of the arms 35 or 36 is swung into a position directly below the slot 37 in the bracket 25. The machine is then started and the lid 11 is closed. During the closing movement of the lid 11, the 35 lower end of the rod 28 will engage the arm which has been swung thereunder and stop the downward movement of the rod 28 before the lid 11 is entirely closed. A continuing closing movement of the lid 11 will 40 cause the hole 19 to be uncovered by the door 20 since the door cannot continue in the path of closing movement of the lid 11 but will merely swing on its hinge 21 and when the lid is entirely closed, as shown in Figs. 45 2 and 3, the door 20 will be opened so that any sounds passing outwardly through the end 14 of the tone arm 13 will pass outwardly through the hole 19 and will be deflected forwardly by the inclined position 50 of the door 20.

By having the arms 35 and 36 at different levels it will be noted that the door 20 can be opened to different extents, for example when the end of the rod 28 engages the 55 upper arm 35 the door will be opened a greater amount than when the arm 36 is in position under the rod 38; these two different positions being respectively illustrated in Figs. 2 and 3.

60 In Fig. 7 I have illustrated a form in which the door 20^a is made up of a number of slats 40 having their opposite ends pivotally mounted in opposite sides of the hole 19^a and these slats 40 are connected by a 65 bar 41 with a link 42 and bell crank lever

43. The bell crank lever 43 is pivotally connected to a bearing 44 secured to the inner surface of the lid 11. In this form of my invention the bell crank lever 43 is pivotally connected to the upper end of the rod 28. In all other respects the construction is similar to that described in connection with Figs. 1 to 6 inclusive and it will be noted that the stopping action of the rod 28 during the closing movement of the lid will effect 70 the opening of the hole 19 by the turning movement of the slats 40. In this manner a distinctly audible talking machine is provided without requiring any large and bulky 75 amplifying means which are usually provided in the front of talking machine cabinets and which require large and separate doors or other means for closing the same and the space usually taken up by this latter mentioned amplifying means and opening 80 can be used for storage purposes if desired. In addition to this a comparatively simple 85 structure is provided which can be manufactured at a comparatively low cost and which in practical use has been found to 90 give exceptionally good results.

While I have described my invention as taking a particular form, it will be understood that the various parts of my invention may be changed without departing 95 from the spirit thereof, and hence I do not limit myself to the precise construction set forth, but consider that I am at liberty to make such changes and alterations as fairly come within the scope of the appended 100 claims.

Having thus described my invention, what I claim as new and desire to secure by Letters Patent is:—

1. A talking machine including a cabinet 105 having a movably connected lid provided with a hole; means within the cabinet for directing the reproduced sounds outwardly through said hole; a door for closing said hole; and means automatically operative 110 during the closing movement of said lid for opening said door; substantially as described.

2. A talking machine including a cabinet 115 having a movably connected lid provided with a hole; means within the cabinet for directing the reproduced sounds outwardly through said hole; a door for closing said hole; a member connected to said door; and means for abutment with said latter member during the closing movement of said lid whereby the door will be prevented from 120 following the movement of said lid and will thereby effect the opening of said hole; substantially as described.

3. A talking machine including a cabinet 125 having a movably connected lid provided with a hole; means within the cabinet for directing the reproduced sounds outwardly through said hole; a door for closing said 130

- hole; a post; a rod pivotally connected to said door; and a member including an arm pivotally mounted on said post and movable into a position so that said rod during 5 the closing movement of the lid will abut said arm and thereby prevent the door from following the closing movement of the lid and effect the opening of said hole; substantially as described.
- 10 4. A talking machine including a cabinet having a movably connected lid provided with a hole; means within the cabinet for directing the reproduced sounds outwardly through said hole; a door for closing said
- hole; a rod pivotally connected to said door; 15 and means including portions arranged at different levels and capable of being swung into abutting position with said rod for limiting its downward movement whereby the door will be opened during the closing movement of said lid; substantially as described. 20
- In testimony whereof I have signed my name to this specification in the presence of two subscribing witnesses.

DONATO DI CARLO.
